NORRIS PETERS, INC., LITHO., WASHINGTON, D. C.

UNITED STATES PATENT OFFICE.

LOUIS BRESIN, OF NEW YORK, N. Y., ASSIGNOR TO ADAMS-WILLIAMS MANUFACTURING CORPORATION, OF NEW YORK, N. Y., A CORPORATION OF NEW YORK
FOLDING AUTOMOBILE TOP

Improvement to a folding automobile top

Serial No. 194,845. Filed Oct. 5, 1917. Patented Feb. 11, 1919.

1,294,038.

Specification of Letters Patent.

Application filed October 5, 1917. Serial No. 194,845.

To all whom it may concern:

Be it known that I, LOUIS BRESIN, a citizen of Russia, and resident of New York, borough of Manhattan, in the county and State of New York, have invented certain new and useful Improvements in Folding Automobile Tops, of which the following is a specification:

This invention is an improvement in folding automobile tops and as to its main features is an improvement on the construction disclosed and claimed in the Williams Patent No. 1,151,314, issued August 24th, 1915. In that patent there is disclosed a bow construction which permits the front of the top to be narrower when in raised or operative position than when in folded position.

The main object of the present invention is to effect this change in width automatically as the top is folded or raised. In the specific construction illustrated in said Williams patent, the front or transverse bow of the top is connected to the two side substantially horizontal bows by links which may extend in the same general direction as the front bow and thereby increase the effective length of the latter when the top is folded and may lie in the same general direction as the side bows when the top is raised so as to decrease the width of the top by an amount approximately equal to the sum of the lengths of the two links.

In my present invention, I provide means whereby this swinging of the said links is effected automatically during the movement of the top and the links are at all times held in the proper position, depending upon the folded or raised position of the top.

Merely as an example of such a construction, I have illustrated one embodiment of my invention in the accompanying drawings. It will be understood that I do not desire to be limited to this specific construction except as defined in the appended claims.

In these drawings,

Figure 1 is a side elevation of a portion of a motor vehicle, the covering of the top being partly removed to show the bows in side elevation with the top raised;

Fig. 2 is a central vertical section through the framework of a portion of the top when partly folded;

Fig. 3 is a top plan view of one front corner of the frame of the top when in raised position;

Fig. 4 is an elevation of the inner side of some of the parts shown in Fig. 3;

Fig. 5 is a view similar to a portion of Fig. 4 but showing the parts approaching folded position;

Fig. 6 is a perspective view of the frame of the top; and

Fig. 7 is a perspective view of a portion of one of the transverse bows on a larger scale.

I have illustrated my invention in connection with a vehicle body having four side wall sections, two of them constituting doors 10 and 11 and the other two constituting rear and intermediate stationary portions. Each of these wall sections is shown as carrying corresponding removable panels 10^a, 11^a, 12^a and 13^a, each of which has a rigid frame and a transparent body portion of glass, celluloid, or the like. The particular manner in which these panels are detachably secured in place and are connected at their upper edges to the frame of the top forms no portion of my present invention and therefore has not been illustrated.

The frame of the top includes a plurality of bows pivotally connected together and of a type commonly known as a "one-man" top; that is, it is pivotally secured to the body only at one point on each side and that point being in the rear of the rear door. The particular number of bows illustrated is not important so far as the present invention is concerned, the frame illustrated being what is commonly known as a five-bow top; that is, there are five transverse members for supporting the fabric or other flexible covering which is secured in any manner common in the art. The particular method of connecting these bows is not important except the mechanism hereinafter described for automatically effecting the variation in width of the front portion of the frame formed by said bows.

As illustrated, there is a main substantially vertical bow 20 having side members 21 pivotally secured to the body in the rear of the rear door and a transverse member 22 for supporting the fabric covering. In the rear of this bow is one or more somewhat similar bows 23 which extend diagonally upwardly and rearwardly. Pivotally secured to the side members 21 of the main vertical bow 20 is a substantially horizontal frame or bow made up of a plurality of pivotally

- connected sections. This bow includes sections 24 which are pivoted to the side members 21 of the bow 20 and mounted to swing about horizontal transversely extending axes.
- 5 Hinged to the front ends of these bow sections 24 are a pair of bow sections 25 which are substantially in alinement with the bow sections 24 when the top is in raised position, as shown in Figs. 1 and 6. The hinges 10 are such that the bow sections 25 may swing about horizontal transversely extending pivots and can swing in only one direction from the alined position shown.
- The front of the main horizontal bow is 15 formed of a bow section 26 which is connected to the front ends of the two bow sections 25 by a pair of short bow sections or links 27. These are each hinged at each end as is shown particularly in Figs. 3 and 5 so 20 that they can swing about vertical axes and can come to positions substantially in alinement with the side bow sections 25, as shown in Fig. 3, or can come to positions substantially in alinement with the front bow 26, 25 an intermediate position being shown in Fig. 5.
- Pivottally connected to the bow sections 24 intermediate of their ends is a bow including 30 side members 28 and a transverse member 29. Between this bow and the upper part of the vertical bow is another and similar bow having side members 30 and a transverse member 31. The side members 30 of this bow are connected to the side members 28 of the bow in advance thereof by links 32 and the side members 30 are connected to the vertical bow above the pivotal supports of the bow members 24 by links 33. The side members 28 are also pivotally connected to the 35 bow members 25 by links 34. Thus, when the hinged connections between the bow sections 24 and 25 are broken by the raising of the front of the main horizontal bow, the two diagonally disposed intermediate bows 40 will simultaneously swing upwardly and rearwardly to and through the positions indicated in Fig. 2.
- It will be evident that in this figure I have 45 not shown the parts in their final folded or lowered position.
- As the most important feature of my invention, I provide means whereby the links 50 27 are swung from the position shown in Figs. 3 and 6 to and through the position 55 shown in Fig. 5 as the top is folded. The particular illustrated embodiment of this means includes links 35 connected at their rear ends to extensions 36 on the links 34 below the pivotal connections 37 between the latter and the bow sections 25. The front 60 ends of the links 35 are connected to inwardly extending brackets 38 on the inner sides of the links 27 and in advance of the pivotal connections between said links 27 65 and the side bow members 25.

In operation, it will be noted that as the top is folded the extensions 36 of the links 34 swing rearwardly and in doing so, exert an endwise rearward pull on the links 35. As the said links 35 are connected to the 70 links 27, the latter are forced to swing inwardly toward or through the position shown in Fig. 5. The parts are so proportioned that when the top is completely folded back, the links 27 will be approximately 75 in alinement with the front transverse bow member 26.

It will be noted that the links 34 and their extensions 36 constitute levers with their fulcrums on the pivots 37 and that these levers, 80 by reason of the pivotal connection between the bows, are compelled to swing about their fulcrums during the folding or raising. As the levers themselves cannot move while the top is stationary in either raised or lowered 85 position, the links 27 are effectively locked at all times. I may allow sufficient looseness at the various pivots and hinges so that the variation in the effective width of the front of the horizontal bow will not necessitate or 90 result in any change in the intermediate bows, but in practice I prefer to make the transverse members 29 and 31 extensible so that their total effective length may vary with the variation in the total effective 95 length of the front of the horizontal bow. No links or other operating mechanism are needed in ordinary practice to effect the variation in the length of the bows 29 and 31 and a simple telescoping or sliding connection is all that is necessary. Preferably, the two bows 29 and 31 are cut in two intermediate of their ends and the two sections are connected by some such parts as those shown in Fig. 7. Here, I have 100 shown one section 29^a of the bow member 29 provided with a thin metal plate 40 with inturned edges to make a channel or groove and have shown the other section 29^b provided with a plate 41 mounted to slide in this 105 groove or channel but held against any other movement in respect to the latter. Thus, as the top is raised or folded and the links 27 swing to lengthwise or transverse positions, the bow sections 24 and 25 swing 110 toward or from each other and the transverse bow members 29 and 31 slightly decrease or increase in total effective length.

Having thus described my invention, what I claim as new and desire to secure by 120 Letters Patent is:

1. A vehicle top having side frame members, a front frame member, two links each having one end pivoted to a corresponding side member and one end pivoted to said front member and means connected to said links for swinging them transversely of the top into or out of substantial alinement with said side members as the top is raised or folded.

2. A vehicle top having a frame, including side members, a front member, connections between said side members and said front member, and means connected to said side members for automatically operating said connections to vary the effective length of said side members and a corresponding and inverse variation in the effective length of said front member by swinging said side members in a vertical plane. 5
3. A foldable vehicle top having a frame including side members, a front member, and means for automatically increasing the effective length of said front member and decreasing the effective length of said side members during the movement of said top to folded position. 15
4. A vehicle top having a frame including side members, a front member, links connecting said side members and said front member, and means connected to said links for automatically swinging them substantially into alignment with said side members or with said front member as said top is raised or folded. 25
5. A vehicle top having a substantially vertical bow, a substantially horizontal bow pivoted thereto and including a plurality of pivotally connected sections, an intermediate upwardly and forwardly extending bow pivoted to said horizontal bow, and means connected to two of said bows for automatically varying the effective width of the front of said top upon the relative movement of two said bows. 30
6. A vehicle top including a substantially horizontal bow, an upwardly and forwardly inclined bow and connections between them whereby the total effective width of the front of said inclined bow is varied upon a relative movement of said inclined bow and said horizontal bow. 40
7. A vehicle top including a plurality of bows, each having a transversely extending cover supporting member and means for varying the total effective width of certain of said transverse members to different extents during the folding of the top, the foremost transverse member having the greatest variation during said movement. 45
8. A vehicle top including a plurality of bows, one of which has a transverse member formed of slidably connected sections and another of which has a front member, side members and links connecting said front 55
- member to said side members, and means pivotally connecting said links and one of said bows for extending the transverse member of said first mentioned bow and swinging said links into positions substantially in alignment with the transverse member of the second mentioned bow during the folding of the top. 60
9. A vehicle top including a substantially horizontal bow formed of a plurality of sections, an inclined bow pivoted thereto, a link connecting one of said sections and said inclined bow, and a link connecting said first mentioned link and another of said sections for automatically moving said sections in respect to each other to vary the total effective width of said horizontal bow upon the relative movement of said horizontal bow and said inclined bow. 65
10. A vehicle top including a substantially horizontal bow including a plurality of pivotally connected sections, an upwardly and forwardly inclined bow, and means including a link connected to said horizontal bow and to said inclined bow for automatically varying the effective width of the front portion of said horizontal bow upon a relative movement of said bows. 70
11. A vehicle top including a bow having side members, a front member, links connecting said front member to said side members, a second bow having a transverse member formed of two slidably connected sections, and connections between said second bow and said links for swinging said links substantially into alignment with said front member and simultaneously elongating said second bow as the top is swung from raised to folded position. 75
12. A vehicle top including a substantially horizontal bow including opposite side members, a front member, and links connecting said side members to said front member, a second bow, links connecting said second bow and said side members, and links connecting said first mentioned links and said second mentioned links for swinging said first mentioned links in the plane of said first mentioned bow and in respect to the members thereof upon the relative movement of said bows. 80
- Signed at city of New York, in the county of New York and State of New York, this 3rd day of October, A. D. 1917.
- LOUIS BRESIN.
